Primary Examiner — Karen S Acker(74) *Attorney, Agent, or Firm* — Larkin Hoffman Daly & Lindgren Ltd.; Craig J. Lervick(57) **CLAIM**

The ornamental design for an electric fireplace, as shown and described.

DESCRIPTION

FIG. 1 is a perspective front view of the electric fireplace in accordance with the present Invention;

FIG. 2 is a front view thereof;

FIG. 3 is a rear view thereof;

FIG. 4 is a top view thereof;

FIG. 5 is a bottom view thereof; and,

FIG. 6 is a side view thereof.

The broken lines including the broken line perimeter and the area within it represent environmental subject matter that forms no part of the claim.
